US00D818309S

(12) **United States Design Patent** (10) Patent No.: **US D818,309 S**
(45) Date of Patent: **** May 22, 2018**

(54) **BOTTLE CAP**

- (71) Applicant: **Industrias Alen, S.A. de C.V.**, Santa Catarina (MX)
- (72) Inventor: **Alpha Edith Jasso Gomez**, Monterrey (MX)
- (73) Assignee: **Industrias Alen, S.A. de C.V.**, Santa Catarina (MX)
- (**) Term: **15 Years**
- (21) Appl. No.: **29/569,745**
- (22) Filed: **Jun. 30, 2016**

(30) **Foreign Application Priority Data**

- Jun. 14, 2016 (MX) MX/f/2016/001848
- (51) LOC (11) Cl. **07-01**
- (52) U.S. Cl. USPC **D7/392.1**; D9/449
- (58) **Field of Classification Search**
USPC D7/391, 392, 392.1, 396.1, 396.2, 397, D7/398, 509, 510, 511, 543; D9/435, D9/436, 438, 447, 449, 450; D10/46.2, D10/46.3
CPC B65D 47/305; B65D 41/16; B65D 47/06
